COMBINED RATTLE AND WHISTLE
Hollis K. Price, Box 701, Oak Hill, W. Va.
Filed June 18, 1962, Ser. No. 203,137
5 Claims. (Cl. 46—177)

This invention relates to new and useful improvements in amusement devices or toys, and the principal object of the invention is to provide a novelty noise maker wherein sounds are produced by a mechanical movement actuated by turning of a crank.

Briefly, the novelty noise maker in accordance with the invention consists of a plate-like body formed with intersecting grooves which slidably receive reciprocable blocks, such blocks being operatively connected to a crank which, when turned, causes the blocks to slide in the grooves of the toy body. An important feature of the invention resides in the provision of coating means in the grooves and in the blocks for producing a scraping or a rattling sound when the blocks are slid in the grooves.

Also, the body of the noise maker is equipped with a laterally projecting handle having a whistle embodied therein, such whistle being caused to blow at intervals when one of the aforementioned blocks slides in its groove into an end portion of the associated handle.

Some of the advantages of the invention reside in its simple construction, highly amusing and entertaining operation, in its novel appearance, and in its adaptability to convenient and economical manufacture.

With the foregoing more important object and features in view and such other objects and features as may become apparent as this specification proceeds, the invention will be understood from the following description taken in conjunction with the accompanying drawings, wherein like characters of reference are used to designate like parts, and wherein:

FIGURE 1 is a top plan view of a noise maker in accordance with the invention;

FIGURE 2 is a side elevational view thereof;

FIGURE 3 is a fragmentary sectional view on an enlarged scale, taken substantially in the plane of the line 3—3 in FIGURE 1;

FIGURE 4 is a fragmentary sectional view, taken substantially in the plane of the line 4—4 in FIGURE 1; and

FIGURE 5 is a fragmentary sectional view, taken substantially in the plane of the line 5—5 in FIGURE 1.

Referring now to the accompanying drawings in detail, the novelty noise maker in accordance with the invention is designated generally by the reference numeral 10 and embodies in its construction a plate-shaped body 11 which may be conveniently molded from plastic material so that the body is hollow with an open bottom and includes a top wall 12 with a depending perimetric flange 13. While this is the preferred form of construction, the body may also be formed from a solid plate, if so desired. In any event, the body 11 is provided in the top thereof with a pair of grooves 14 which intersect each other at right angles at the center of the body, these grooves having dovetailed or undercut side walls 15 and bottom walls 16 which are molded integrally with the top wall 12 of the body. The grooves 14 are open-ended, so that a pair of reciprocable blocks 17 may be slidably inserted into the grooves.

The blocks 17 are hollow and also preferably molded from plastic, each block having an open bottom and including a top wall 18, a pair of downwardly divergent side walls 19 and a pair of end walls 20, as is best shown in FIGURE 3. The side walls 19 of the blocks slidably engage the side walls 15 of the grooves and since the walls 19 are downwardly divergent and the walls 15 are dovetailed or undercut, the blocks are prevented from

2

moving upwardly out of the grooves. The top walls 18 of the blocks are provided with pivot pins 21 which are connected at longitudinally spaced points to a crank 22, the latter having an upwardly offset free end portion 22' provided with a crank handle or finger grip 23. It will be apparent from the foregoing that when the crank 22 is turned, the blocks 17 will be caused to reciprocate in the grooves 14, this mechanical movement as such being well known so that a detailed explanation thereof is believed to be unnecessary.

One important feature of the invention resides in adapting the aforementioned mechanical movement for sound producing purposes so that the device may be used as a novelty noise maker. This involves the provision of sets of spaced parallel, raised ribs 24 extending transversely on the bottom walls 16 of the grooves 14, such ribs being molded integrally with the walls 16 but terminating short of the groove side walls 15 so that the lower edges of the side walls 19 of the blocks 17 may slide along the bottom walls 16 of the grooves without interfering with the ribs. Also, the end walls 20 of the blocks 17 have their lower edge portions provided with recesses 25 to afford clearance for the ribs 24 when the blocks are slid in the grooves. However, a resiliently flexible brush or reed 26 is disposed within each of the blocks 17, being secured to the associated pivot pin 21, the lower end of the brush or reed engaging and skipping over the ribs 24 to produce a scraping or a rattling noise when the blocks 17 are slid in the grooves 14 by turning of the crank 22.

While the crank 22 is being turned with one hand, the body 11 is held by the other hand applied to an elongated handle 27 which may be formed integrally with the body so as to project laterally to one side therefrom, as illustrated. As an element of novelty, the handle 27 may assume the form of a miniature baseball bat, and it will be noted that the handle is connected to the body in alignment and in communication with one of the grooves 14 and that the handle overlaps the body to some extent so that the end portion of the associated groove actually extends into the adjacent end portion of the handle, as indicated at 14'. Moreover, the extent of reciprocation of the blocks 17 in the grooves 14 is such that the block which slides in the groove aligned with the handle 27 actually enters the groove region 14' within the handle, where a step 28 is formed to close off the recess 25 in the adjacent end wall 20 of that block, so that as the block enters the handle, it compresses air in the groove portion 14'. The air so compressed flows through a restricted opening 29 into a hollow interior 30 of the handle and, in conjunction with an opening 31 which communicates the handle interior with the atmosphere, a whistling noise is produced at intervals, each time the block enters the handle and forces air into the groove portion 14'. Thus, when the toy is in operation and the crank 22 is turned, a continuous rattling sound is produced by the scraping of the reeds 26 on the ribs 24 and, at one point during each turn of the crank, a whistle is sounded by forcing of air into the handle 27.

If desired, additional whistles may be provided at the open ends of the grooves 14, similar in construction to the whistle embodied in the handle 27. The upward offset of the crank portion 22' provides sufficient clearance for the crank to be turned without interference with the handle 27, as will be understood.

While in the foregoing there has been described and shown the preferred embodiment of the invention, various modifications may become apparent to those skilled in the art to which the invention relates. Accordingly, it is not desired to limit the invention to this disclosure, and various modifications and equivalents may be resorted to, falling within the spirit and scope of the invention as claimed.

What is claimed as new is:

1. In a noise maker, the combination of a body provided with intersecting grooves, each groove having a bottom wall and spaced transverse ribs on said bottom wall, hollow blocks reciprocable in said grooves past one another, a common crank operatively connected to said blocks for reciprocating the same when the crank is turned, and resiliently flexible reeds mounted in said blocks and engageable with said ribs to produce sound when the blocks are reciprocated.

2. In a noise maker, the combination of a body provided with a groove, a handle connected to said body and having an end portion of said groove extending thereto, said end portion of said groove forming an air chamber in said handle, air passages provided in said handle in communication with said air chamber to provide a whistle, a block reciprocable in the groove of said body in and out of said air chamber, means for reciprocating said block whereby to compress air in said chamber and sound said whistle, and coacting means in said groove and in said block for producing a rattling sound when the block is reciprocated.

3. In a noise maker, the combination of a body provided with intersecting grooves, each groove having a bottom wall and transverse ribs on said bottom wall, hollow blocks reciprocable in said grooves past one another, a common crank operatively connected to said blocks for reciprocating the same when said crank is turned, resiliently flexible reeds provided in said blocks and engageable with said ribs to produce a rattling sound when the blocks are reciprocated, a handle connected to said body in alignment with one of said grooves and having an end portion of said one of said grooves extending thereto to provide an air chamber, air passages provided in said handle in communication with said air chamber to provide a whistle, one of said blocks being reciprocable in and out of said air chamber to compress air therein and sound said whistle.

4. In a noise maker, the combination of a plate-like body having upper and lower surfaces and provided in its upper surface with intersecting grooves, each of said

grooves having downwardly divergent side walls and a bottom wall, spaced transverse ribs provided on the bottom wall of each groove, hollow blocks reciprocable in said grooves past one another, each block having a top wall substantially flush with the upper surface of said body, each block also having a pair of downwardly divergent side walls in sliding contact with the side walls of the associated groove and having an open bottom, common means operatively connected to said blocks for reciprocating the same, and resiliently flexible reeds disposed in said hollow blocks each reed having one end thereof secured to the top wall of the associated block and its other end in scraping engagement with said ribs to produce a rattling sound when the blocks are reciprocated.

5. The device as defined in claim 4 together with a handle connected to said body and having one end portion of one of said grooves extending thereto, said groove extending into said handle providing an air chamber in the handle, said air chamber having closed sides and a closed inner end and an open outer end in communication with said last mentioned groove, air passages provided in said handle in communication with the inner end of said air chamber and coacting therewith to provide a whistle, the one of said blocks in said last mentioned groove being reciprocable into and out of said air chamber and conforming substantially to the cross-section of said chamber, said last mentioned block constituting a piston and compressing air in the chamber when reciprocated thereto, whereby to expel air from said chamber through said passages and sound said whistle.

10 15 20 25 30

5. The device as defined in claim 4 together with a handle connected to said body and having one end portion of one of said grooves extending thereto, said groove extending into said handle providing an air chamber in the handle, said air chamber having closed sides and a closed inner end and an open outer end in communication with said last mentioned groove, air passages provided in said handle in communication with the inner end of said air chamber and coacting therewith to provide a whistle, the one of said blocks in said last mentioned groove being reciprocable into and out of said air chamber and conforming substantially to the cross-section of said chamber, said last mentioned block constituting a piston and compressing air in the chamber when reciprocated thereto, whereby to expel air from said chamber through said passages and sound said whistle.
